UNITED STATES PATENT OFFICE.

HERBERT G. MACKINNEY, OF PROVIDENCE, RHODE ISLAND.

DESIGN FOR TRIMMING FOR ARTICLES OF JEWELRY.

SPECIFICATION forming part of Design No. 13,861, dated April 17, 1883.

Application filed March 13, 1883. Term of patent 7 years.

To all whom it may concern:

Be it known that I, HERBERT G. MACKINNEY, a citizen of the United States, residing at Providence, in the county of Providence and State of Rhode Island, have invented a new and original Design for Trimming for Articles of Jewelry; and I do hereby declare that the following specification, taken in connection with the accompanying drawings, forming a part of the same, is a full, clear, and exact description thereof.

This design relates to that variety of trimmings for articles of jewelry which is known as "gallery," the same consisting of an ornamental strip of metal adapted to be secured to breastpins, bracelets, lockets, and other articles as a surface ornament, or to form a portion of the contour or outline of the article.

Referring to the drawings, Figure 1 represents a breastpin which is ornamented with a

trimming embodying the design. Fig. 2 shows a piece of the trimming detached.

The design consists in a strip, A, having one of its edges indented so as to form projections *a*, the contour of each of which is the arc of a circle, and having, also, perforations *b*, which are circular in outline, and are located partially or wholly in said projections.

The strip A may be generally straight, as shown in Fig. 2, or curved so that its indented edge is convex, as shown in Fig. 1, or curved so that its indented edge will be concave.

What I claim, and desire to secure by Letters Patent, is—

The design for a trimming for articles of jewelry, substantially as described and shown.

HERBERT G. MACKINNEY.
